UNITED STATES PATENT OFFICE.

CHARLES B. WHIPPLE, OF SPRINGFIELD CENTER, NEW YORK.

MEANS FOR COLLECTING AND CARRYING OFF SMOKE AND ODORS FROM STOVES.

No. 853,530.

Specification of Letters Patent.

Patented May 14, 1907.

Application filed November 2, 1906. Serial No. 341,789.

To all whom it may concern:

Be it known that I, CHARLES B. WHIPPLE, a citizen of the United States, residing at Springfield Center, in the county of Otsego 5 and State of New York, have invented certain new and useful Improvements in Means for Collecting and Carrying Off Smoke and Odors from Stoves, of which the following is a specification.

10 The object of my invention is to provide a simple and efficient construction of device for collecting and carrying off smoke and odors incident to cooking.

With this object in view, the invention consists in certain constructions and arrangements of the parts hereinafter described and particularly pointed out in the appended claims.

For a full understanding of the invention 20 and the merits thereof and also to acquire a knowledge of the details of construction of the means for effecting the result, reference is to be had to the following description and accompanying drawings, in which:

25 Figure 1 illustrates in side elevation and in full lines my improved device for collecting and carrying off smoke and vapor, and also shows in dotted lines the inoperative position of the hood; Fig. 2 is an enlarged sectional 30 view of the device; and, Fig. 3 is a detail perspective view of one of the clamping devices employed.

Corresponding and like parts are referred to in the following description and indicated 35 in all the views of the drawings by the same reference characters.

Referring to the drawings, the numeral 1 designates a cook-stove of any conventional type and 2 the smoke outlet pipe or flue 40 thereof.

45 My improved smoke and odor collector comprises a bell-shaped hood 3 which is designed, in operative position, to be located above the cook-stove and said hood is provided at its upper contracted end with a preferably integral tubular shank 4 which extends substantially at right angles to the main portion of the hood. This shank or stem 4 is designed to be slipped into the upper end of a main suspending pipe 5 and said stem 4 is provided at diametrically opposite points with keepers 6, either one of which is designed to be engaged with the outwardly projecting free end of a latch spring 7 secured 55 to the adjacent end of the main suspending pipe 5. By this means, as is evident, the

hood 3 may be suspended with its mouth downward so as to collect the smoke and odors arising from the stove and may also be swung around so that its mouth will face upwardly so as to be in an inoperative position out of the way. In either of these two positions, the latch 7 engages with one of the keepers 6 so as to not only maintain the hood in one position, or the reverse, but also to detachably connect the stem or shank of the hood to its suspending pipe 5. The pipe 5 is provided near its outer end with a damper 5^b, which may be swung to extend across the pipe and close the same so that when the bell 70 is removed bodily from its suspending pipe, the latter may be closed and thus interfere in no wise with the proper draft of the smoke pipe 2.

The main suspending pipe 5 is provided in 75 the present instance with the branch pipe 8, which opens upwardly therefrom between the damper 5^b and the inner end of the pipe 5 and the inner ends of both the main suspending pipe 5 and its branch 8 are designed to 80 extend into openings formed for them in the smoke pipe 2 and face upwardly as indicated at 5^a and 8^a. Flanges or collars are secured to the main pipe 5 and its branch 8 and these flanges or collars are adapted to extend 85 around the openings formed in the smoke pipe 2, so as to form a snug fit and limit the inward movement of the said suspending pipe and its branch, and the inner ends of the smoke pipe and its branch are preferably of 90 such a diameter that they terminate far short of the opposite wall of the smoke pipe 2 and therefore do not materially interfere with the draft of the said smoke pipe.

In order to detachably secure the entire device to the smoke pipe 2 which constitutes a support therefor, I provide in the present instance, two clamping collars 9, one for the main suspending pipe 5 and one for its branch. Each of these clamping collars consists of an 100 intermediate portion formed of two members 10 curved as shown and spaced apart and connected at their ends so as to produce a substantially crescent shape structure and said intermediate portion formed by these 105 two members is connected at its ends to the hinged end portions 11 that are provided at their extremities with interlocking devices 12.

In the practical operation of applying the device to the smoke pipe 2, the inner ends of 110 the main suspending pipe 5 and the branch 8 are inserted in the openings formed to re-

ceive them and the two clamping devices 9 are clamped around the collars or flanges of the suspending pipe and its branch and encircle the smoke pipe, as illustrated. The 5 members 10 of the intermediate portion of the clamping device are diverged and extend one over the upper side of its respective pipe end, and the other underneath the same, as clearly illustrated in the drawings.

10 It is evident that the branch pipe 8, from its arrangement and construction will materially assist the main suspending pipe 5 to hold the hood 3 in a stable or secure condition above the stove, while at the same time, 15 the said branch pipe 8 affords an increased draft which may be taken advantage of whenever necessary.

From the foregoing description in connection with the accompanying drawings, it will 20 be seen that I have provided a very simple and efficient construction of device for collecting and carrying off smoke and odors from articles that are being cooked upon the stove and that the device may be readily assembled 25 and attached to and detached from the smoke pipe whenever desired, and one in which, if it is not desired to entirely remove the device from the smoke pipe, the collecting hood may be swung up to an out-of-the-way 30 or inoperative position whenever the device is not in actual use.

Having thus described the invention, what is claimed as new is:

1. A device of the character described, 35 comprising a hood, a suspending pipe for said hood, said pipe being provided with a branch and the pipe and its branch being adapted to be inserted through apertures in the stove, and means for securing the suspending 40 pipe and its branch to the smoke pipe.

2. A device of the character described, comprising a bell, a suspending pipe from which the bell is suspended, the suspending pipe being adapted for insertion in an aperture in the smoke pipe of a stove and provided with a collar adapted to surround such an aperture, and a clamp consisting of an intermediate portion composed of an upper and a lower member adapted to engage the collar at the top and bottom, and two hinged end portions connected to the intermediate portion and arranged for interlocking engagement around the said smoke pipe. 45 50

3. A device of the character described, consisting of a main suspending pipe provided with an upwardly facing inner end and arranged for insertion through an opening in the smoke pipe of the stove, said main suspending pipe being provided with a damper and with a branch suspending pipe leading 60 upwardly therefrom between said damper and the inner end of the main pipe, said branch suspending pipe being arranged for insertion in another aperture in the smoke pipe of the stove and also having its inner 65 end facing upwardly, a latch secured to the outer end of the main suspending pipe, and a hood provided with an angularly disposed stem adapted to telescope in the outer end of said branch suspending pipe and provided 70 with diametrically disposed keepers any one of which is arranged for interlocking engagement with said latch.

In testimony whereof I affix my signature in presence of two witnesses.

CHARLES B. WHIPPLE. [L. S.]
